C. P. ROSS

TRAMCAR

Filed Aug. 30, 1922

UNITED STATES PATENT OFFICE.

CLYDE P. ROSS, OF CHICAGO, ILLINOIS.

TRAMCAR.

Application filed August 30, 1922. Serial No. 585,118.

To all whom it may concern:

Be it known that I, CLYDE P. Ross, a citizen of the United States, residing at Chicago, in the county of Cook and State of Illinois, 5 have invented a certain new and useful Improvement in Tramcars, of which the following is a specification.

My invention relates to an automatic dumping tram car and to an adjustable dump cam 10 adapted to be adjustably positioned along the path of the tram, thus permitting control of the point of discharge of the material contained in the tram. Other objects will appear from time to time throughout the specification and drawings.

I illustrate my invention more or less diagrammatically in the accompanying drawings, wherein—

Figure 1 is a side view of the dumping 20 installation;

Figure 2 is a detail view of the dump cam illustrating the cooperation of the tram bottom therewith.

Like parts are designated by like characters throughout.

A is any suitable chute or source of supply for which coal or other materials are dumped into the tram B, which rides on the wheels C along the horizontal tracks D. The 30 outward bottom of the tram B is closed by a swinging gate E pivoted as at E' and having an arcuate bottom F provided with cam engaging rollers G. It will be understood that when the gate E hangs, the arcuate portion 35 F snugly closes the bottom of the tram car. The tram B is moved along the track D, for example by the cable H which may be actuated by any suitable power source not herein shown. Beneath the track D is a second, cam 40 supporting track I. Upon this track rides the cam J which may be constructed as a single casting or in any other suitable way and which has a domed or humped back J' comprising an upward curve or incline J² at either end, together with a substantially horizontal portion therebetween. The cam is 45 mounted on the wheels K which ride on the track I and is provided with any suitable clamp L, herein diagrammatically illustrated, which serves to grip the track rail in 50 response to the rotation of the screw M, the clamp being formed of two opposed track engaging portions which may be loosened or

drawn together about the upper flange of the track by the rotation of said screw. 55

It will be realized that while I have illustrated an operative mechanism, many changes might be made in the size, number, shape and relation of parts without departing from the spirit of my invention. 60

The use and operation of my invention are as follows:

I illustrate a tram car in which any material, for example, coal, may be laterally transported. The invention is illustrated in 65 connection with horizontal transportation but applicant does not wish to limit himself to a horizontal track or a horizontal movement of the carriage. A double system of tracks is used, an upper track upon which 70 the conveying tram car rides and a lower track along which the cam is adjusted. Obviously other means than a separate track might be used for positioning the tram. In coal dumping, for 75 example, the point in which it is desired to dump coal from a lateral conveyor frequently changes and I therefore provide a cam which may be positioned at any point along 80 the path of travel of the tram. It is then clamped at the point of use, to prevent shifting in response to contact of the tram. When the tram is loaded with coal, the gate E with the arcuate plate F closes the bottom of the 85 hopper shaped car, but the gate is held in position merely by gravity and without a positive lock. When the tram car is conveyed along the track D to the point where 90 the cam is positioned, the roller G rides up on the slope or incline J² and the gate E and plate F are therefore rotated into the 95 position shown by the dotted lines in Figure 1 and in second position in Figure 2. The load of the tram car is released, when the cam is reached and the length of the cam is sufficient to hold the gate in raised position long enough to permit the escape of the entire load, even if the operator does not stop the tram car over the cam.

I claim:

In a coal handling installation a coal delivery means, a track underlying said delivery means, an open-topped coal conveying bucket mounted upon said track and means for conveying it therealong, means for limiting the inward travel of said bucket when it 100

105

reaches a point aligned beneath said coal delivery means, a radius gate mounted beneath said carriage, and adapted normally to close its bottom, a second track underlying and aligned with said first mentioned track, a gate tripping cam carriage mounted thereon and means for adjusting its position on said track, said cam carriage comprising an inclined surface at either end, an intermediate substantially horizontal surface connecting

said inclined surface, a cam engaging element upon said gate, aligned with said cam carriage and adapted to override it and open the gate, in response to relative movement of the conveying carriage and the cam carriage. 15

Signed at Chicago, county of Cook and State of Illinois, this 23rd day of August, 1922.

CLYDE P. ROSS.
